UNITED STATES PATENT OFFICE.

GEORGE H. GOLDSMITH, OF OLD ORCHARD, MAINE, ASSIGNOR TO SACO-LOWELL SHOPS,
OF BOSTON, MASSACHUSETTS, A CORPORATION OF MASSACHUSETTS.

SPINDLE.

1,182,558.

Specification of Letters Patent.

Patented May 9, 1916.

Application filed July 3, 1914. Serial No. 848,935.

To all whom it may concern:

Be it known that I, GEORGE H. GOLDSMITH, of Old Orchard, in the county of York and State of Maine, a citizen of the United States, have invented a new and useful Improvement in Spindles, of which the following is a full, clear, and exact description, reference being had to the accompanying drawings, forming a part of this specification, in explaining its nature.

The present invention relates to spindles for spinning machines and which are especially adapted for spoolers.

The essential object of the invention is to so construct the usual parts of the spindle as to perform additional functions to those ordinarily performed with resulting advantages, pertaining especially to lubrication and also to the manipulation or removal of the spindle blade and attached parts during the running of the spinning machine or spooler on which the spindle is used.

The invention can best be seen and understood by reference to the drawings, in which—

Figure 1 shows the spindle in side elevation, a portion of the spindle rail also being shown in cross section to illustrate the manner of attaching the spindle thereto. Fig. 2 shows the spindle mainly in cross vertical section. Fig. 3 is the same as Fig. 1 excepting that the spindle blade and whirl thereon are shown in an elevated position.

1 represents the rail, 2 the base of the spindle. This base extends upwardly through the rail and is provided with an enlarged top end or head 3 forming a flange bearing against the top surface of the rail and assisting in securing the base thereto. The base is otherwise retained by means of a nut 4 thereon which when tightened bears against the under side of the rail locking the base securely to it. The top end or head 3 of the base, as may be seen by reference to Fig. 2, is made substantially cup-shaped, the same comprising a bottom 5 with an upturned edge or rim 6, these parts combining to form an oil chamber 7 and presenting a cylindrically rounded side surface 8.

9 is an opening which extends through the bottom 5 of the head and into the base.

10 is the spindle blade which turns within the opening 9 of the base and head. Carried by the blade is a whirl 11. This whirl 55 has the general form of an inverted cup and

fits over the head 3 in the manner of a cover closing the chamber 7 thereof. The whirl 11 comprises a top portion 12 by which it is attached to the blade and from the outer edge of which depends a rim 13 which extends telescopically over the cylindrical side 8 of the head 3. The rim 13 of the whirl presents a cylindrically-rounded exterior surface around which the tape is passed, the surface of the whirl being preferably slightly crowned that the tape may run properly upon it. With the parts thus arranged it will be seen that the exterior surface of the rim lies normally outside of and concentric with the surface of the head whereby the surface of the rim may occupy a position substantially of both extension and continuity to the surface of the head when the blade and whirl carried by it are moved away from the base. It will also be observed that the lower edge of the rim 13 of the whirl lies very close to the spindle rail when the whirl is in its normal position, the distance separating this edge from the spindle being less than the ordinary width of the tape which runs upon the whirl.

The operation is as follows: Oil placed within the chamber 7 will enter the opening 9 containing the spindle and thereby keep the spindle properly lubricated at all times. Access is had to the chamber 7 either for purposes of inspection or for adding oil thereto simply by raising the blade and attached whirl, and this may be accomplished at any time during the operation of the machine simply by grasping the blade and lifting it into an elevated position as shown in Fig. 3. When this is done the tape normally running around the rim of the whirl will run off the lower edge thereof onto the cylindrically rounded side surface 8 of the head of the base which provides a proper bearing for the tape. In this connection it is to be observed that the head is preferably provided with an outwardly turned annular flange 14 (see Fig. 2) which will prevent the tape running off the surface 8 of the head when deposited thereon by the elevation of the whirl as aforesaid. When the blade and whirl are replaced or dropped into their normal position as shown in Fig. 1 the bottom edge of the rim of the whirl will engage the tape running upon the head as aforesaid and force the same against the spindle rail. The resulting effect is that the tape will

become automatically forced back upon the whirl or, in other words, jump back thereon when the whirl and blade will be rotated in the usual manner. This adaptability of 5 the parts enables the blade and whirl not only to be elevated during the operation of the machine for the purpose above referred to but also permits of the removal of the entire blade and whirl as occasion may require 10 without stopping the machine.

Having thus fully described my invention, I claim and desire to secure by Letters Patent of the United States:—

1. The combination comprising a spindle 15 base, a head presenting a cylindrically-rounded exterior side surface, a blade mounted to turn within said base and a whirl carried by the blade having a rim presenting a cylindrically-rounded exterior 20 side surface adapted to receive a tape, said rim overlapping said head and with said surface of the rim normally exterior to and concentric with that of the head whereby said surface of the rim may occupy a position 25 substantially of both extension and continuity to the surface of the head when said blade and whirl carried by it are moved away from the base substantially as and for the purposes set forth.

2. The combination comprising a spindle 30 base, a head presenting a cylindrically-rounded exterior side surface, a blade mounted to turn within said base and a whirl carried by the blade having a rim 35 presenting a cylindrically-rounded exterior side surface adapted to receive a tape, said rim overlapping said head and with said surface of the rim normally exterior to and concentric with that of the head whereby 40 said surface of the rim may occupy a position substantially of both extension and continuity to the surface of the head when said blade and whirl carried by it are moved away from the base and a tape running upon the 45 surface of the whirl pass therefrom onto the surface of the head, and other means assisting in restoring the tape to the surface of the whirl during the running of the tape when the whirl is returned to its normal 50 position.

3. The combination comprising a spindle rail, a spindle base extending through and below the rail with a head above the rail and bearing against it, said head presenting 55 a cylindrically-rounded exterior side surface, a blade mounted to turn within the base and movable away from and toward the same, and a whirl carried by the blade having a rim presenting a cylindrically- 60 rounded exterior side surface adapted to receive a tape, said rim normally overlapping said head down to a point closely adjacent said rail and with the exterior side

surface of the rim normally exterior to and concentric with that of the head whereby 65 said surface of the rim may occupy a position substantially of both extension and continuity to the surface of the head when said blade and whirl carried by it are moved away from said base, substantially as described. 70

4. The combination comprising a spindle base, a head hollowed to form an oil chamber, said head presenting also a cylindrically-rounded exterior side surface, a blade 75 mounted to turn within said base and a whirl carried by said blade and fitting over said head closing the chamber thereof, said whirl comprising in part a rim presenting a cylindrically-rounded exterior side surface 80 adapted to receive a tape, said rim overlapping said head and with the surface of the rim normally exterior to and concentric with that of the head whereby said surface of the rim may occupy a position substantially of both extension and continuity to the surface of the head when said blade and whirl carried by it are moved away from the base to afford access to said chamber and whereby also a tape running upon the 85 surface of the whirl may then pass onto the exterior surface of said head.

5. The combination comprising a spindle base, a head presenting a cylindrically-rounded exterior side surface, said base and 95 head having an opening therein adapted to receive a spindle blade, said head having within it an oil chamber in communication with said opening, a spindle blade mounted to turn within said opening and movable 100 away from or toward said base, and a whirl carried by the blade, said whirl comprising a cover for said head having the general form of an inverted cup fitting over and enclosing the oil chamber in the head, said 10 whirl consisting in part of a rim overlapping said head and presenting a cylindrically-rounded exterior side surface adapted to receive a tape, said surface of the rim lying normally exterior to and concentric 11 with that of the head whereby it may occupy a position substantially of both extension and continuity to the surface of the head when the blade and whirl carried by it are moved away from the base and a tape 1 running upon the surface of the whirl to pass therefrom onto the surface of the head, and other means cooperating with said rim to return the tape to the surface of the whirl during the running of the tape when the 1 whirl is moved toward the base and returned to its normal position.
